UNITED STATES PATENT OFFICE

2,051,230

ADJUSTABLE ROOF FOR HAYSTACKS

Fred N. Tillotson, Battle Creek, Iowa

Application August 19, 1935, Serial No. 36,830

7 Claims. (Cl. 108—2)

The object of my invention is to provide an adjustable roof for hay stacks of simple, durable and inexpensive construction and which may be readily, quickly and easily erected or dismantled and which, when erected, is firmly and securely braced against all the strains to which devices of this kind are ordinarily subjected.

More specifically, it is my object to provide a roof of this character in which the roof may be supported in an elevated position while the hay stack is being erected, and then lowered to position for resting upon the hay stack regardless of the height to which the stack is made, and then, when the hay stack shrinks and lowers, the roof will automatically move downward with the hay stack to thereby prevent the entrance of strong winds between the top of the hay stack and the roof, to thereby insure the roof against being blown off of the stack by high winds.

More specifically, it is my object to provide an automatic wedge lock device connected with cables for raising the roof, which wedge lock device will be inoperative during the upward movement of the roof by the cables but which will automatically permit downward movement of the roof and prevent upward movement of the roof when the cables are slack.

A further object is to provide improved means for supporting the uprights and for holding them in their upright positions against both outward and inward movement relative to each other when erected, so that the roof may freely move up and down within the area defined by the corner posts.

My invention consists in the construction, arrangement and combination of the various parts of the device whereby the objects contemplated are attained, as hereinafter more fully set forth, pointed out in my claims, and illustrated in the accompanying drawing, in which:

Figure 1 shows a top or plan view of a roof embodying my invention.

Figure 2 shows a side elevation of same with the roof supported in an elevated position. The dotted lines in said figure show two of the supporting posts in a partly elevated position to illustrate the manner in which the posts are moved to upright positions.

Figure 3 shows an enlarged detail view illustrating the wedge engaging member.

Figure 4 shows an enlarged detail view of the windlass and ratchet device for elevating the cables.

Figure 5 shows a detail vertical sectional view through a corner of the roof and a portion of

the adjacent upright, and illustrating the wedge locking device in locked position to prevent upward movement of the roof.

Figure 6 shows an enlarged detail side view illustrating the cable supporting pulley at the top of the upright; and

Figure 7 shows a horizontal sectional view on the line 7—7 of Figure 5.

Referring to the accompanying drawing I have used the reference numeral 10 to indicate generally a hay stack roof. This has not been illustrated in detail but is preferably made in sections so that it may be easily transported and stored. At each corner of the roof there is a downwardly extending bracket 11, through which is extended a pin 12. This pin is detachably mounted in the bracket and is held in place by small pins 13, or the like, extended through it.

There are four uprights to the supporting roof. Each is preferably made of a metallic I beam 14. I have provided a base for each upright consisting of a flat member 15 to rest upon the ground and which is secured in position to the ground by means of the stakes 16 which may be driven through openings in the base. The upright member is pivotally supported to this base. At the top of each upright is a bracket 17 in which a pulley 18 is mounted. There are four of these uprights, and four cables 19 are secured to the upper ends of the uprights so that the movements of the uprights outwardly relative to each other are limited by these cables. Secured to the upper end of each upright are two guy rods 20 extended in opposite directions outwardly away from the roof, and on each guy rod there is a turn buckle 21 for adjusting its length. Each guy rod is provided with a stake 22 driven into the ground. These guy rods may be adjusted by means of the turn buckles to firmly and securely hold each post in an upright position and in such manner as to prevent inward movement of the upper end of the post, and by this means each post is firmly supported in an upright position.

By this arrangement of the uprights and their connecting cables and the pivoted bases to which the uprights are connected, the device may be erected very readily and easily by first placing two of the uprights with their bases in properly spaced apart position and staked to the ground. Then the two uprights may be elevated to upright positions and the guy rods staked to the ground and properly adjusted. Then the other two uprights may be erected in the same manner, and when thus erected, will all be inde-

pendently supported in their positions regardless of the roof.

Mounted upon each upright is a windlass indicated generally by the reference numeral 23 and having a cable 32 fixed to and wound thereon. The windlass is provided with a ratchet device 25 so that the cable may be held in position when so desired, or the ratchet device may be disconnected to permit the cable to play out freely.

10 Slidingly mounted upon each upright is a bracket consisting of a plate 26 having a wedge block 27 fixed to its inner surface. Two metal straps 28 are fixed to this plate 26 and extended around the upright to form a bracket device capable of freely sliding up and down on the upright.

Between the adjacent web of the upright 14 and the plate 26 there is a wedge member. This member comprises a frame 29, as shown in Figure 3, with a roller 30 at its central portion, and two chains 31 extending upwardly and connected to the adjacent end of one of the cables 32, which cable is passed over the pulley 18 and fixed to and wound around the adjacent windlass 23. The plate 26 is also connected to the cable 32 by means of a chain 33, and this chain, as shown in Figure 5, will be slack when the chains 31 are tight. By this arrangement it is obvious that an upward pull upon the cable 32 will first raise the frame 29 and its wedge member 30, and then if the upward pull is continued, will raise the plate 26. When, however, the cable 32 is slack, an upward movement of the plate 26 will cause the wedge 27 to coact with the wedge member 30 and lock the plate 26 against further upward movement; and under the same conditions, the plate 26 may freely move downwardly because the wedge member 30 will engage the frame 29 and both will move downwardly as far as the slack will permit. This plate 26 is provided with an opening at 34 to receive the pin 12 at the corner of the roof. This opening is preferably made relatively large so that the pin may have a limited tilting movement relative to the plate 26.

45 In practical operation the uprights are erected and held in upright position in the manner heretofore described, then the roof 10 may be assembled and rested upon the ground between the uprights. When this has been done the pins 12 may be inserted in position and the cables 32 connected to the chains 31 and 33. When this has been done, obviously the roof may be moved to an elevated position by winding up the windlasses 23, and after the roof has thus been elevated, the hay stack will be formed under it in the ordinary manner. When the hay stack is fully completed or partially completed, the windlasses are operated to lower the roof until it rests upon the top of the hay stack. When in 60 this position with the cables 32 slack, the roof may freely descend by gravity so that it continues to rest upon the top of the stack regardless of the amount of shrinkage of the stack. Due to the fact that the pins 12 are loosely mounted in the plate 26 the roof may move upwardly and downwardly freely whether it is in a horizontal position or not, and it may be tilted to a considerable angle in either direction without binding.

70 In the event of a high wind or tornado, or the like, the roof will at all times be in position resting firmly upon the top of the stack so that wind cannot enter under the roof to blow it away. In addition to this, however, in the event that any 75 corner of the roof should be moved upwardly by

the wind a slight distance, the wedge 27 will then engage the adjacent wedge member 30 and thereby securely lock this particular corner of the roof against further upward movement, so that for all practical purposes the roof is firmly held 5 in position resting on top of the stack and in such position that high winds cannot enter under the roof or have a tendency to blow it away from the stack.

I claim as my invention:

10 1. An adjustable roof for hay stacks and the like, comprising a roof, a series of supporting uprights, means for elevating the roof relative to the supports, and means for slidingly connecting the roof with the uprights, comprising a 15 member slidingly mounted on an upright and pivotally connected to the roof and a wedge device between the roof and upright shaped to permit free downward movement of the roof and to prevent upward movement of the roof. 20

2. An adjustable roof for hay stacks and the like, comprising a roof, uprights at the corners thereof, a bracket slidingly mounted on each upright, means for pivotally and detachably connecting the roof corners to said brackets, a cable 25 for each bracket to pull it upwardly, and a wedge device for each bracket for permitting the bracket to move freely downwardly and to wedgingly lock the bracket against upward movement relative to the adjacent upright. 30

3. An adjustable roof for hay stacks and the like, comprising a roof, uprights at the corners thereof, a bracket slidingly mounted on each upright, means for pivotally and detachably connecting the roof corners to said brackets, a cable 35 for each bracket to pull it upwardly, and a wedge device for each bracket for permitting the bracket to move freely downwardly and to wedgingly lock the bracket against upward movement relative to the adjacent upright, a part of 40 said wedge device being connected to the adjacent cable and designed to release the wedge device when the cable is drawn upwardly to thereby permit the upward movement of the bracket.

4. An adjustable roof for hay stacks and the like, comprising a roof, uprights at the corners thereof, a bracket slidingly mounted on each upright and having an opening in one side, a pin 45 fixed to the adjacent corner of the roof and extended into said opening, a wedge carried by the bracket, a wedge engaging member to coact with said wedge, a cable attached to each of said brackets for elevating it, and a chain for connecting each wedge engaging member with the adjacent cable, said chain being of such length 50 that when the cable is moved upwardly it will first elevate the wedge engaging member and move it upwardly to inoperative position, and then upon further upward movement of the cable the bracket will be elevated, said parts being 55 so arranged that when the cable is slack the said bracket and its wedge member may freely move downwardly.

5. In a roof for hay stacks and the like, the combination of a roof, four uprights at the corners of the roof, cables connected to the upper ends of the uprights to limit their outward movement relative to each other, a base to which the lower end of each upright is pivoted, means for securing each base in position, and two guy rods 60 for each upright to limit their inward movement relative to each other. 65

6. An adjustable roof for hay stacks and the like, comprising a roof, a supporting upright for the roof, means for elevating the roof relative 70 75

to the support and for operatively disconnecting the roof from the elevating means so that it may move downwardly by gravity, and an automatic device associated with said roof and upright and shaped to permit free downward movement of the roof and to prevent upward movement thereof when the elevating means is operatively disconnected from the roof.

7. An adjustable roof for hay stacks and the like, comprising a roof, a supporting upright for

the roof, means for elevating the roof relative to the support and for operatively disconnecting the roof from the elevating means so that it may move downwardly by gravity, and an automatic wedge device associated with said roof and upright and shaped to permit free downward movement of the roof and to prevent upward movement thereof when the elevating means is operatively disconnected from the roof.

FRED N. TILLOTSON. 10
